TUBE BENDING MACHINE

Filed Oct. 12, 1923

FIG. 1.

FIG. 2.

FIG. 3.

Inventor
John H. Hawes
by Wilkinson & Huota

UNITED STATES PATENT OFFICE.

JOHN HENRY HAWES, OF LONDON, ENGLAND.

TUBE-BENDING MACHINE.

Application filed October 12, 1923. Serial No. 668,151.

To all whom it may concern:

Be it known that I, JOHN HENRY HAWES, a subject of the King of Great Britain, of 14 to 19 Tottenham Mews, Tottenham 5 Street, London, England, have invented a new and useful Improvement in or Relating to Tube-Bending Machines, of which the following is a specification.

This invention relates to tube bending machines and has for its object to provide an improved construction or modification of the tube bending machine described in my previous application for Patent Serial No. 623,470.

According to my said application the tube is bent around a radius wheel or former by means of a bending roller mounted on a lever and adapted to travel over the back of an intermediate shield through which the bending force is applied at a position from 10° to 25° but preferably about 15° in advance of the bending point.

According to the present invention a radial lever is provided with a screw device for 25 adjusting the roller in a radial direction to suit the different sized pipes and formers or radius wheels, and the said radial lever is also fitted with an angular gauge by which the correct working angular position of the 30 bending roller in relation to the bending point may be quickly and accurately determined for the different sizes of pipes and radius wheels.

The said gauge may either form a base 35 against or upon which a separate set square or the like may be placed to ascertain the correct position in relation to the tube to be bent or the gauge may be provided with a sliding set square or projecting or folding arms for the same purpose.

The accompanying drawings show two constructions of the improved pipe bending machine,

Figure 1 is a plan,

Fig. 2 is a front elevation of Fig. 1, and Fig. 3 is a semi-diagrammatic plan view showing a modified construction.

In the construction shown in Figs. 1 and 2, a radial bifurcated lever *e* is employed 50 fitted with a slide *k* which carries the bending roller *f* and is adapted to be adjusted longitudinally of the radial lever *e* by a screwed spindle *l* which extends out through the handle end of the said lever and is provided with a milled head *m* or other suitable means by which it may be operated.

The handle end of the radial lever *e* is preferably provided with an elongated boss *n* over which a tubular member *o* indicated in dotted lines may be placed to increase 60 the length of the handle and secure the required leverage without using the screwed spindle *l* as a handle for the larger sizes where considerable force is necessary.

Upon the face of the radial lever *e* is 65 fitted a gauge consisting of a bar *p* having mounted thereon a sliding pointer or set square *q* the edge *q'* of which nearest the radius wheel *c* is always at 90° with the gauge bar *p*. *i* is a stud adapted to be 70 fitted in one of a number of holes *j* in the base plate and forming an abutment against which the length of pipe *h* preceding the bending point may bear. The said stud *i* is formed with a grooved side *i'* and one 75 curved and grooved side *i''*.

The arrangement is such that when any 80 of the set of radius wheels stops and shield are assembled with the pipe *h* to be bent in position, the radial lever *e* and bending roller *f* are adjusted by the screwed spindle *l* until with the roller *f* in contact with the shield *g* the edge of the set square is parallel with the pipe *h* to be bent and the bending roller *f* will be in the before mentioned correct angular position to perform the bending operation on thin gauge tubes 85 with efficiency and without injury to the same.

The sliding set square *q* on the gauge 90 may be adapted to rotate about the gauge bar *p* so that it may be turned over to project on either side of the bar *p* as may be most convenient in use.

If desired, and according to a modified 95 construction, the gauge may consist of a straight trued face placed at such an angle that a set square or the like placed against the face of the gauge may be used instead of the sliding square.

In the modified construction shown in Fig. 3, the set square *q* which slides on the gauge bar *p* is provided with two gauging edges *q'* *q''*, and the machine is arranged 105 so that the lever *e* may be used on the left hand side as well as the right hand side of the machine.

When the lever is used to bend a tube by a forward movement on the right hand side of the machine as shown in full lines, the 110 gauging face *q'* is employed and when the lever is used on the left hand side of the

machine, as shown in dotted lines, the gauging face q^2 is employed.

The machine is provided with adjustable stops on the right and left hand sides.

5. What I claim as my invention and desire to secure by Letters Patent is:—

1. A tube bending machine of the kind referred to comprising the combination of a radius wheel or former and shield with 10 coacting faces grooved and proportioned to the tube to be bent, a radial lever adapted to turn on the axis of the radius wheel or former, a bending roller mounted upon said lever, a screw device for adjusting the position of the bending roller longitudinally 15 of the radial lever, an angular gauge mounted upon said radial lever and adapted to permit of the correct angular working position for the bending roller being quickly 20 and accurately determined for the different sizes of tubes and radius wheels.

2. A tube bending machine of the kind referred to comprising the combination of a radius wheel or former and shield with 25 coacting faces grooved and proportioned to the tube to be bent, a bifurcated radial lever adapted to turn on the axis of the radial wheel or former, a slide mounted in the bifurcated end of said radial lever, a 30 bending roller mounted on said slide a screwed spindle extending longitudinally through the handle of said radial lever and beyond the end thereof, and serving to adjust the position of the slide which carries 35 the bending roller, a gauge fitted upon the radial lever and adapted to permit of the bending roller being adjusted by the screw so as to engage the pipe to be bent at the required angular position in advance 40 of the bending point.

3. A tube bending machine of the kind referred to comprising the combination of a radius wheel or former and shield with coacting faces grooved and proportioned to 45 the tube to be bent, a bifurcated radial lever adapted to turn on the axis of the radial wheel or former, a slide mounted in the bifurcated end of said radial lever, a bending roller mounted on said slide a 50 screwed spindle extending longitudinally through the handle of said radial lever and beyond the end thereof, and serving to adjust the position of the slide which carries the bending roller, a gauge bar fitted upon 55 the upper face of said radial lever, a pointer

or set square mounted upon said gauge bar and adapted to slide thereon for the purpose of quickly determining the correct angular position of the bending roller in advance of the bending point and in relation to the pipe to be bent.

4. A tube bending machine of the kind referred to comprising the combination of a radius wheel or former and shield with 60 coacting faces grooved and proportioned to the tube to be bent, a bifurcated radial lever adapted to turn on the axis of the radial wheel or former, a slide mounted in the bifurcated end of said radial lever, a bending roller mounted on said slide, a 65 screwed spindle extending longitudinally through the handle of said radial lever and beyond the end thereof, and serving to adjust the position of the slide which carries the bending roller, a gauge bar fitted upon 70 the upper face of said radial lever, a pointer or set square adapted to slide on said gauge bar, and hinged thereon so as to be turned to project above or below said bar for the purpose of quickly determining the correct 75 angular position of the bending roller in advance of the bending point and in relation to the pipe to be bent.

5. A tube bending machine of the kind referred to comprising the combination of a radius wheel or former, and shield with coacting faces grooved and proportioned to the tube to be bent, a bifurcated radial lever adapted to turn on the axis of the radial wheel or former, a slide mounted in the bifurcated end of said radial lever, a bending roller mounted on said slide a 80 screwed spindle extending longitudinally through the handle of said radial lever and beyond the end thereof, and serving to adjust the position of the slide which carries 85 the bending roller, a gauge bar fitted upon the upper face of said radial lever, a pointer or set square mounted on said gauge bar and adapted to slide thereon for the purpose of quickly determining the correct 90 angular position of the bending roller in advance of the bending point, two gauging edges on said pointer or set square so arranged as to permit of the bending lever being used on the right or left hand sides 95 of the machine for bending a tube by the forward or backward movement of said lever.

JOHN HENRY HAWES.
